UNITED STATES PATENT OFFICE.

FRANCIS H. RICHARDS, OF HARTFORD, CONNECTICUT, ASSIGNOR, BY MESNE ASSIGNMENTS,
TO AMERICAN TYPOGRAPHIC CORPORATION, A CORPORATION OF NEW JERSEY.

ART OF MAKING TYPES AND TYPE-BARS.

No. 919,220.

Specification of Letters Patent.

Patented April 20, 1909.

Application filed October 21, 1901. Serial No. 79,359.

To all whom it may concern:

Be it known that I, FRANCIS H. RICHARDS, a citizen of the United States, residing at Hartford, in the county of Hartford and 5 State of Connecticut, have invented certain new and useful Improvements in the Art of Making Types and Type-Bars, of which the following is a specification.

This invention pertains to the manufacture of impression-faces or characters, and 10 particularly to the manufacture of a plurality of the same which shall have the intimate relationship possessed by the component members of an integral line of type.

15 The present invention relates in particular to a method of making characters and more especially printing types from a blank of proper material, and to a method of making a series of such types from or on a blank to 20 form an integral line of type which it is intended shall constitute the printing portion of a logotype or typebar (linotype) adapted for use in the topographic art for printing composition.

25 The invention constituting the subject-matter herein disclosed is closely related to that illustrated, described and claimed in the application of Darien W. Dodson, Serial No. 600,152, filed July 22, 1896, to which I have 30 permission to refer, and is, in fact, in the nature of an improvement upon the invention set forth in that application. According to the Dodson method of making separate types along a blank without the application 35 of heat from an extraneous source, the types are made in succession by the subjection of successive portions of the face of the blank to a rolling treatment as the result of rolling the blank and the successively working dies 40 with relation to each other—the movement of the type-making members which results in this rolling treatment being, however, a simple progressive one in which the members are caused to approach each other and while 45 the die is in engagement with the blank to progressively vary the angular relation of the impression device and the blank during the progress of impressing the latter; that is to say, the type-making operation is confined within the limits of a movement of approach, engagement, and subsequent recession of the members, the several movements 50 being progressive or continuously in one direction and the movement of approach, engagement and recession occurring in the

order specified. There is also included in said Dodson method further features which are involved in the general method of producing consecutive predetermined types along a proper blank, consisting in the preliminary preparation of the portions of the blank to which the dies are to be applied in order to roughly form each respective portion approximately to the shape of the type or type-block to be made therefrom. In addition to this the making of spaces at proper points along the edge of the blank is contemplated in that invention for the purpose of receiving the flowage endwise of the blank occurring at each type-making operation and 70 which would otherwise distort or disturb or tend to distort or disturb a finished type at the rear.

The present improvements are, in their essence, an extension of the idea involved in 75 the Dodson method of making types, and in their practical application—as in the making of types according to the method disclosed in the said Dodson application—the entire operation involved in the production of each 80 type is completed before the making of a consecutive type of the composition is commenced. As distinguished from that invention, however, the treatment to which the material of the blank is subjected by each 85 die in the manufacture of the corresponding type according to the present invention, is such as to accomplish the formation of the type gradually and the subjection of the material lying in the edge of the blank to a 90 series of reductions. Thus the types result, according to the invention disclosed herein, from a successive step-by-step progressive treatment or operation, not only in the complete forming and finishing of the individual 95 types, but in the production of the entire series or line of type considered as a unit, as well.

Many efforts have been made to produce from a mass of type-formable material, by 100 the action of a die, a type suitable for use in, and which would satisfactorily meet the requirements of, the topographic art, in point especially of sharpness, definition and durability, and to combine a number of such 105 types in a line of composed types or type faces, in the endeavor to produce a typebar that would satisfy the demands of the art for successful commercial application. Such attempts to form the type have generally 110

been made, so far as I am aware, as the result of direct pressure exerted by the die on the type-formable material unaccompanied by any concurrent or subsidiary force or movement designed to facilitate the production of an accurate and sharply-defined counterpart of the type-forming die. Experiment has demonstrated, however, that such a mode of operation is ineffective to produce a satisfactory printing type. The natural cohesion of the material caused during the shearing action of the cutting edges of the die, *i. e.*, those edges which determine the contour of the base of the type-block 10 where it joins the body or stock of the blank, and portions adjacent to or in what will eventually form the impression face of the type to be dragged or flow in the direction of the die movement, resulting in a type-like character 15 which cannot be properly called a type, inasmuch as it is incapable of producing a satisfactory printed impression. If a type-like character made in this manner be examined (especially with the aid of a glass) it will be noticed that the impression face thereof is convex or rounding to a considerable extent, being higher at and adjacent to the center of the type-lines than at the edges thereof, and for this reason while it simulates 20 the characteristics of a proper type, it cannot ordinarily be used to make a satisfactory printed impression. This deformation or lack of sharpness and definition is particularly noticeable in the fine projections and hair-lines, which, in the case of a type of 25 relatively small proportions, remain unformed, or at least imperfectly formed. Even if this rectilinear motion of the die be continued to a point depthwise of the blank 30 more than sufficient it would seem to more than cause the bottom of the die cavity to contact with the stock, the mass within the die is carried bodily in the direction of die movement leaving the finer indentations 35 and hair-lines of the die cavity unfilled. The flowage manifestly taking place along the line of least resistance, has been demonstrated by experiment to be, in the ordinary typebar-blank, in a direction other than 40 that which would completely fill the sharp angular recesses and hair-line spaces of the die. Such flowage has been shown to take place laterally downward under the edges of the die and even in the body of the blank 45 itself to a degree sufficient, in some cases, to produce sensible alteration in the cross-sectional form of the blank at a point within the sphere of flowage action. This mode of making type on the usual typebar-blanks 50 results, therefore, in a type the edges of whose impression face are lacking in sharpness and definition.

When it is attempted to make upon a typebar-blank a second type at a point which 55 brings an already formed type thereon with-

in the flowage radius (for so I may term the maximum distance in any particular direction in which a movement in the mass of material occurs sufficient in extent to disturb or displace a formed surface—a radius whose position and length is established and determined by the particular mode of die operation employed) an additional factor requires consideration; to wit, the disposal of excess or surplus material in the field of action of the die and which is sheared by the latter from the material building up and forming the type-block. This excess or surplus material, in connection with the formative stresses of the working die, not only variously modifies the flowage concurring with and created by the advancement of the die into the blank, in the absence of any provision for controlling its direction of movement, but also invariably results in the overriding of the adjacent type or in the displacement of the same from its proper relative position as such types exist in ordinarily spaced composition. The production, therefore, of a typebar having a line of consecutive wrought types upon its edge involves, generally speaking, something more than the repetition of a type-making operation at points along the edge of a blank, by reason of the fact that owing to the nearness of the types one to the other, in consequence of the ordinary spacing subsisting in typographic composition, the flowage of the material of the blank in excess of that necessary to build up each type-block 90 surmounted by its proper impression face 95 tends to displace or disturb the metal in an adjacent and finished type at the rear. Such indeed will be the result, as experience has shown, unless measures are adopted either inherent in the mode of treatment applied 100 by the working die or in some other way to protect this finished type from the flowage of the material set up by such die and the stresses induced by its working.

It is evident from the statement hereinbefore embodied, that during the making of a type according to the method disclosed in the said Dodson application, the die is presented to the stock of the blank at varying angles, moving, in fact, along a path corresponding to that portion of a cycloid at or adjacent to the cusp of such curve. The motion of the die with relation to the blank is not, therefore, merely a relatively straight line or rectilinear movement, but is more in 110 the nature of a compound movement effective to produce the type as the result of a wrought-like process; but the period of the working of the material is so short, and by reason of the fact that it is not repeated again and again, the stock is not worked and forced increment by increment into the cavity of the die to thereby effectually and completely fill the angular recesses and minute indentations thereof. A type formed 115 120 125 130

according to the Dodson method, therefore, does not generally possess the highest possible degree of definition and sharpness. Furthermore, if that species of the said method 5 of making types disclosed in that application is carried out in which the blank is first cross-slotted to isolate a type-blank on the edge of the main blank, the typebar-blank is rendered less able to withstand the crushing action of the die. Moreover, by reason of this preliminary isolation of the type-blank and its roughing out a plurality of operations are necessary, consuming time in their performance and requiring a plurality of tools 10 or operative devices.

In practicing my present invention I avoid the necessity altogether of setting off type-blanks before the dies are brought into action, and I subject each type-formable portion of 20 the main blank to repeated actions or operations, which, for the purpose of producing symmetrically formed types, are preferably alternated from side to side of the mass. These repeated operations result in the 25 gradual reduction of the material under the die to shape, and they are of such character that they effect the strengthening and finishing of the base portions of the type or type-block where the latter connects with the 30 stock of the blank besides condensing and compacting the impression and other faces of the type. In consequence of the repeated workings to which the stock is subjected, the filling of the angular portions and hair-line 35 spaces of the die cavity is accomplished to a high degree of perfection. These results I accomplish by combining with a relative movement of the members to cause the penetration of the blank by the die, a relative 40 subsidiary movement of the parts during at least a portion of the feeding period. Such subsidiary movement (and herein there exists an important feature of my present improvements) is of a character and in a direction 45 calculated to force the excess or surplus material or cause it to flow laterally or cross-wise of the blank, that is, in a direction away from an adjacent type. This relative subsidiary movement of the members (i. e. the 50 blank and the die or die-like instrumentality) may be of divers characters, provided it is of such a nature as to effect a continued and progressive working or reduction of the stock of the blank and thereby cause the 55 same to assume a form which is a counterpart of the die or like instrumentality with an incidental movement of the surplus material laterally of the blank. Thus, the to and fro subsidiary movement may be one of 60 oscillation through a comparatively small arc while the two members are in contact, or either member may be reciprocated to and fro relatively to the other through a comparatively short path. As distinguished 65 from an oscillation about a fixed axis; on the

other hand, either member may be rolled back and forth in contact with each other.

In the drawings which accompany this specification, I have illustrated divers forms of mechanisms typical of practical and operative devices for making types and integral lines of types according to the present method, but in so illustrating the specific mechanical details and organization thereof shown I wish it understood that various other forms 70 of mechanism may be used for accomplishing the results attained by the operation of the conventional forms of devices shown, as, in general, a practical operative machine for producing type after type, will embody refinements and additional features not herein shown, for the reason that they are not deemed to be necessary to or involved in the production of types according to the fundamental method herein disclosed. 80

In these drawings, Figure 1 is mainly a side elevation of a simple species of mechanism for making types as the result of a feeding movement and a relative subsidiary motion in the nature of a to-and-fro or alternating rolling movement of the die while in contact with the blank. Fig. 2 is a view at right angles to Fig. 1, a part of the mechanism being broken away. Fig. 3 is a top view of the mechanism. Fig. 4 is a sectional view illustrating the relative motion of the die with respect to the blank during the making of a type. Fig. 5 is a view similar to Fig. 1, but illustrates a mechanism in which the relative subsidiary movement results from the oscillation of the blank about an axis extending longitudinally or axially thereof. Fig. 6 is mainly an end elevation of the mechanism shown in Fig. 5, looking from the left in that figure. Fig. 7 is a plan view of the mechanism shown in Figs. 5 and 6. Fig. 8 is a vertical cross-section of a mechanism suitable for carrying out the present method of making types and lines of types, the mechanism in this case being adapted to produce a relative subsidiary motion in the nature of a translatory movement of comparatively small magnitude, the rectilinear motion in this case being imparted to the die. Fig. 9 is a cross-sectional view upon an enlarged scale through 105 a die and a blank in engagement therewith, illustrating the formation of a type and showing the members in their relative position at the close of the type-making operation. 110

Similar characters of reference designate 120 corresponding parts in all the figures of the drawings.

Although the present invention, as before stated, is applicable to the production of characters, designs, die-faces, types, etc., in 125 cameo or in intaglio, indented or in relief, I contemplate more especially its application to the making of raised characters or characters in relief on the edge of a proper blank, that is, to the making of types; and while it 130

will therefore be set forth more particularly herein as applied to such a purpose, it will be understood that it is not limited to the production of types alone.

5 As already explained, the said Dodson application discloses a method of making type and lines of type in which the type-die is rolled across the edge of the blank transversely to the line of length thereof, this rolling movement of the die being a simple progressive one with the result that the type-die is applied to the blank at varying angles. The stock of the blank is consequently worked to some extent to effect the filling of the cavities 10 and recesses of the die, but by reason of the fact that the die remains in contact with the blank only while it is being rolled forwardly across the edge thereof, the stock is not subjected to repeated operations and is not 15 therefore treated in such a manner as to best and most effectually fill the angular recesses and hair-line spaces of the die cavity. Nor is the working of the stock, in the practical application of that method, such as to produce a wrought type having faces, and especially an impression face, hardened, condensed and strengthened by repeated actions 20 and operations. According to the present method of making type and lines of type, on the contrary, the type, at each type-making 25 operation, is formed as the result of repeated actions to which the stock is subjected, and by reason of these successive and repeated actions, the stock is worked and wrought to 30 fully, and it might be said absolutely, fill the finest cavities and indentations within the die. The natural result of these repeated forging and swaging pressures (well known to 35 those familiar with processes of working and forging metal) is the condensing of the stock and the finishing of the impression face and other surfaces of the type to a high degree of 40 smoothness and uniformity of texture.

The blank, which may be of any material 45 suitable for the purpose, ordinarily the usual type-metal alloy, but preferably an alloy possessing such characteristics as will give a harder and denser blank than the ordinary composition of type-metal is capable of producing, is of any proper and desired form. Thus the blank upon which, or from which, the consecutive types are to be made may be 50 one in which that portion for making the types constitutes the edge of a blank approximately type-high, or the blank for the types 55 may be a separate and independent piece distinct from the type-carrier or type support by means of which the types are held at the proper height in the form. Moreover, such a 60 blank may be of any desired length;—it may have a length corresponding to the single logotype or line of types to be made, or the types may be made on a continuous blank which is severed at the proper points to make

the several logotypes or lines of type. While 65 the blank may be of cast metal, it will preferably be of a wrought nature, especially as regards those portions thereof which are concerned in building up the several types, as I 70 find such a metal is best suited to the production of types according to the present method.

Any proper die may be used for working the stock into the desired type. It will, of course, have the proper configuration to produce the given type as its counterpart. The 75 application of the present invention is not limited to the use of a die or dies of any particular construction, since the various operations to be performed on the stock, being in their nature separate and independent from 80 each other, may be performed by separate and distinct instrumentalities, but the manufacture of types is most conveniently carried out by those dies in which the boundary walls of the die cavity intersect the outer 85 face of the die in comparatively sharp edges. Such a die is set forth in my application, Serial No. 79,360, filed October 21, 1901. These comparatively sharp edges act as incising or shearing devices for dislodging the 90 stock of the blank during the relative working of the type-making members and forcing portions thereof into the die cavity and filling the same. Each die may be applied to its proper portion of the blank in various 95 ways, and the foregoing subsidiary movement adverted to may be caused to take place at any time subsequent to the application of the die to the blank and prior to the 100 separation of the members, that is, the completion of the type-making operation. Thus the die may be caused to penetrate the blank and to roughly shape the stock to the form of the die, and it may even be fed a considerable distance thereinto for the purpose of 105 filling the die cavity and blocking out the type before the relative subsidiary motion is imparted to the members. In fact, different instrumentalities may be used, the one for 110 roughing-out or shaping the stock approximately to the form of the type-block to be produced, and the other for finishing such block. On the other hand, this subsidiary motion may be coextensive in point of duration with that of the engagement of the die 115 and blank. For the same purpose the blank may also be variously treated preliminarily to the application thereto of the successively selected dies. According to the Dodson invention hereinbefore adverted to, each portion of the blank is, in general, subjected to a preliminary operation or treatment, whereby 120 a part at least of the material in excess of that needed for the making of the type is removed, subsequent to which the die is 125 brought into engagement with the portion thus preliminarily prepared, various instruments for this purpose separate and distinct

from the die being shown. In carrying out the present invention, a similar mode of preliminarily preparing successive portions of the blank may be employed, or the die itself

5 may be of such construction as to perform, when operated, the same function as accomplished by the trimming tools illustrated in the drawings of the said Dodson application.

Instead of preliminarily preparing each 10 portion of the blank prior to the application to that particular portion of the proper die, the edge of the blank may, as a whole, be treated either by rolling said edge or by trimming the same to cause such edge to assume a form or shape best calculated to assist the working of the die in filling the cavity. Various forms of blanks are set forth in applications filed by me. The blank may also be otherwise treated to assist and facilitate 20 the action of the die. I have myself made certain improvements in blanks and which blanks are peculiarly adapted for use herein.

In effecting the production of a type as the 25 result of repeated reductions and shapings of the stock of the blank, various relative motions, herein designated as subsidiary motions, may be imparted to the members while in engagement. Thus the blank may be oscillated relatively to the die about an 30 axis, which, in order that the surplus material may be forced away from a finished type at the rear, that is, sidewise of the blank, will extend substantially in line with the line of types to be formed, that is, lengthwise of the 35 blank. During the oscillation of the blank about this axis, which oscillation, it may be here noted, will be through a comparatively small arc, in order that the integral connection of the forming type with the stock of the 40 blank shall not be destroyed, the two members will be preferably fed together. While this oscillatory movement is taking place, the oscillatory axis may remain fixed with relation to the framework of the mechanism 45 or it may be shifted contemporaneously with the feeding movement either at the same rate at which the members are fed together or at a different rate. I do not contemplate that the present method of making types 50 shall be restricted to any specific relation or condition of rest or motion in respect of such axis, various methods of making types particularly embodying these features being set forth in other applications filed by me.

55 Instead of oscillating the blank about a fixed axis or one which has a progressive predetermined movement, the types may be produced as the result of rocking or rolling the die across the edge of the blank, or vice 60 versa, while the two are in contact, both of these modes of producing a type resulting in the repeated shaping and working of the stock of the blank effectively filling the cavity of the die, while the direction of the rela-

tive working movement is such as to force 65 material, in excess of that needed for the making of the type, transversely of the blank, or toward its sides.

Although I consider that the most satisfactory types are produced when such a relative motion is imparted to the members as will cause the angular relation of the axis of the working die and that of the forming type to repeatedly and positively vary, I do not wish to limit the making of types and lines of 70 type, according to the present method, to the employment of a subsidiary or working movement such as described, as the members may be so operated that a relative movement of a different description occurs. 75 Thus such movement may be one along a substantially straight line. For example, one of the members may be vibrated to and fro, or moved parallel to itself, while the two members are in contact. Of course this 80 translatory movement will be comparatively small in magnitude; that is, the excursion of the moving member to and fro will be through a comparatively short path, in order that the forming type may not have its 85 integral connection with the stock broken, although it is free to bend to and fro through a small angle while held within the die. The blank may be subjected to these repeated operations in any suitable manner, but while 90 hand operated tools may be employed for the purpose, suitable mechanism will ordinarily be used. Moreover, while different tools may be employed for operating upon 95 separate portions of the blank, I have 100 deemed it preferable to make use of a single tool or die, as when one of the two coöperating members is moved properly relative to the other, a single die is sufficient to subject the stock to all of the various operations 105 which it undergoes before becoming a finished type. Thus the removal of material in excess of that needed for the making of a type is an operation separate and distinct 110 from that by which the stock of the blank is worked up and by successive shapings reduced to the form of the type-block, these two operations may be carried on simultaneously, and it being apparent from the foregoing statement that this excess material is 115 worked or forced out laterally of the blank, that is, transversely to the line joining the character-field of the forming type with the character-field of an adjacent type. Although the type or type-block is formed as 120 the result of the application of forces applied in various directions to the stock of the blank by the boundary walls or faces of the die-cavity, the working outward of excess material, being in its nature and results distinct from this operation, may be accomplished by other faces associated with the die and in fact constituting a part thereof. 125

While, therefore, these two operations, that is, the working outward of the excess material and the shaping of the stock into a type-block, may be effected by separate instrumentalities, each die may itself embody these various working means. Such a die, combined with mechanism for causing it to perform its proper function, is set forth in my application, Serial No. 79,360, and although 10 for the convenient disclosure of the present method of making types and typebars such a form of die is indicated in the present drawings, it is deemed unnecessary to specifically describe the same, reference being had for 15 this purpose to my last-mentioned application.

I do not deem it necessary so far as the present invention is concerned that the subsidiary movement should be of the same 20 kind as long as it lasts at each type-making operation, since it may vary in any desired manner. Neither do I wish to restrict the application of the present invention to any particular direction of relative feed movement 25 of the type-making members together. The direction of such feed movement may be substantially in line with the axis of the die during the whole period in which the die penetrates the material of the blank, or the 30 direction of such feed movement may be at an angle thereto, and along a substantially straight or a curved path. Likewise, this relative motion of the members together at each type-making operation may be for a 35 portion of the feed movement substantially in line with said axis, and during another portion of such feed movement at an angle thereto.

Referring now more in detail to the conventional forms of mechanism set forth in 40 the drawings accompanying the present specification for making types and lines of type, it will be understood from what has already been stated, that the mechanisms 45 herein illustrated are not the preferred forms thereof for practicing the present improvements, since in a complete operative mechanism for making determinate and closely related types in succession, a selective apparatus will, usually be embodied, whereby upon 50 the selection of a particular die the corresponding type will be automatically made upon the proper portion of the edge of the blank, under the control of an operator. 55 The various mechanisms shown illustrate means for accomplishing various subsidiary movements, and especially those above adverted to, during the feeding of the type-making members together.

60 Referring to Figs. 1, 2, 3, and 4 in the first instance, a suitable supporting framework, designated in a general way by B, is shown upon which various operative parts are mounted. Dies for forming various types 65 are designated without preference by D, and

for convenience of operation and selective location at the working point of the machine, they are mounted upon a carrier C, herein shown as a rotary carrier or die-wheel, secured to a shaft 2, mounted in bearings 3, 3. 70 As the mechanism illustrated in these figures is adapted to produce a type as the result of rolling the die to and fro across the edge of the blank while in contact therewith, these bearings 3, 3 are in this instance erected upon 75 a slide 4, adapted to hold a to-and-fro movement in suitable guides 4', 4' at the upper portion of the framework B. In order to permit the rotary adjustment of the carrier C and thereby allow the positioning of a 80 given or desired die at the working point of the machine, an adjusting collar 5, is, according to the present construction, mounted upon the shaft 2 and connected therewith by a key and keyway construction, (not shown). 85 This adjusting collar 5 is fixedly secured to a pinion 6, normally in mesh with a fixed rack 7, secured to a portion of the machine framework. It is evident from this construction that when the slide 4 is reciprocated to and fro with the pinion 6 in mesh with the rack 7, a positive to-and-fro angular movement will be given to the die-carrier C (see the angle included between the lines x, x, Fig. 4), and hence a die thereon located at the working point will be rolled to and fro in a direction crosswise of the edge of the blank situated thereat, with its line of length disposed transversely to the plane of the carrier C. A spring 8 is provided tending to thrust the adjusting sleeve 5 and pinion 6 to the left in Fig. 2 and maintain the pinion in engagement with the rack. A to-and-fro or reciprocatory movement may be imparted to the 90 slide 4 by any suitable means, that herein shown comprising an eccentric 9, serving, through the usual strap and a transmitting link 10 to impart an oscillatory motion to a 95 vibrating lever 11, pivoted at its lower end as by a pivot-rod 11' to the framework and at its upper end pivotally connected by a link 12 to lugs 13, extending downward from the lower side of the slide 4. The eccentric 9 is affixed to a driving-shaft S, normally at rest, but caused to rotate at will in the illustrated 100 form of mechanism from a driving-pulley 15, (loosely mounted upon the shaft S and which may be continuously driven from any suitable source of power, not shown), through the following means:—A starting lever 16 is 105 fulcrumed intermediate its ends by a pin 17 to the frame B and supports a catch 18, normally located (through the action of a spring 16') in the path of a clutch arm 19, pivoted to a fixture 21, secured to the driving-shaft S. The catch 18 when engaged with the arm 19 110 serves to hold the latter out of contact with a pin 20, fixed relatively to the pulley 15 and extending axially thereof. Upon the withdrawal of the catch from contact with the 115 120 125 130

arm 19 however the latter is released and is thrust, by a spring 22 in this instance, into the path of the projecting pin 20. The rotation of the driving-shaft S now ensues as the 5 result of the continued rotation of the driving-pulley 15, and a to-and-fro motion is imparted to the slide 4.

The blank herein shown in the form of a short-length blank and designated in a general way by G, may be supported by any suitable means, and the two members fed 10 against each other in any proper way. According to the construction illustrated in the figures specified the blank is shown supported in a blank-carrier H, between side pieces h, h' of which the blank is clamped by clamping screws 23, 23. In this instance the blank is fed against the die, the blank-carrier being supported upon a slide 24, and 15 although this carrier is mounted in vertical guideways to have a movement toward and away from the die-carrier, it will be obvious from what has already been described that the construction might also be such as to 20 give a feed movement of a different character. Movement is in this case imparted to a slide in its guideways by means of an arm 25 pivoted at one end to the frame of the machine and at its opposite end carrying a 25 cam-roller 26, in operative engagement with a cam 27, secured to a shaft 28, which shaft may be rotated by means such as those to be described. Intermediate its ends the lever 25 is pivoted to the slide 24 supporting 30 the blank-carrier H, and it is evident that when the lever 25 is turned about its pivotal connection with the frame of the machine, the slide, and hence the blank-carrier, will be correspondingly moved. The lever 25 35 is actuated by means of the cam 27, already described, driven from the shaft 28, which shaft is rotated intermittently from the driving-shaft S, according to the present construction, by means of an eccentric 29, 40 serving to actuate a pawl 30, spring-pressed into engagement with a ratchet-wheel 31, secured to the shaft 28. It is evident that when the driving-shaft S is in rotation, a 45 step by step rotative movement is imparted to the shaft 28, and hence, by the rolling of the cam-roll 26 upward on the cam 27, the slide 24 is raised, and a blank in the blank-holder H caused to press against the die selectively located at the working point.

50 In order to prevent the starting arm 16 from assuming a position when brought to its releasing position and let go, in which it would again disconnect the driving-pulley 15 from the driving-shaft S, a notched disk 55 32 is in this instance provided upon the shaft 28, being so placed and disposed as to adapt it to coöperate with a roller 33, mounted on the arm 16, and being operative upon the initiation of the rotation of the shaft 28 60 to withhold the arm 16, and hence the catch

18 from engagement with the clutch-arm 19 until the shaft 28 has been rotated step by step a full rotation, consuming a period in so doing that will suffice to permit the reciprocation of the slide 4 a sufficient number 70 of times.

In the simple species of mechanism illustrated a manually operative feed-screw 34 is shown for traversing the blank in the blank-carrier step by step to bring successive portions of its edge to the working point of the mechanism. This feed - screw is mounted in suitable bearings and as shown 75 engages with a nut 34', located between projections 34'', extending downward from the blank-carrier, while the feed-screw may be provided with a graduated hand disk 35 for its convenient manipulation.

Referring now to the mechanism set forth in Figs. 5, 6, and 7, which mechanism, it may be premised, is herein exhibited for the purpose of illustrating a construction adapted to produce a type as the result of a subsidiary movement in the nature of an oscillatory or angular movement imparted in 80 this case to the blank, B' as before designates the supporting frame for the various operative parts of the mechanism. The die-carrier C' is similar to the carrier C already described except that the carrier C' has a 85 fewer number of dies D mounted upon it. In this particular construction also the feed movement for effecting the penetration of the blank by the die is imparted to the die-carrier instead of to the blank, as in the 90 previously described mechanism. To this end the die-carrier C' is mounted in a rock-frame L, whose shaft 36 is journaled in arms 37, 38, extending from a sleeve 39, mounted 95 to swing upon a shaft 40, extending between 100 the side pieces 41, 41' of the machine framework. The sleeve 39 of the swing-frame is confined to a movement axially of its supporting shaft by means of a collar 42, attached to the shaft 40, the opposite end of 105 the sleeve abutting against the adjacent side-frame. In this instance the arm 38 of the swing-frame is extended in the form of a hand lever 43 for conveniently effecting the movement of the swing-frame, and hence 110 compressing the blank by a selectively located die. An adjustable stop device for limiting the downward or compressing movement of the die-carrier is also shown, designated in a general way by M, and comprising 115 a threaded stop-rod m' pivoted to ears m² extending from the side piece 41, whereby the rod may be swung into the slot between lugs m³ extending from the lever 43 or moved away from engagement with such lugs to 120 permit the swing-frame to be thrown back. A lower stop face is formed by a nut m⁴ preferably held firmly in place as by a jam nut m⁵. Upwardly the play of the frame and 125 its supported parts is limited by an adjust- 130

able nut m'' engaging with the threaded rod m' . A stop-pin 44, having a finger-piece 44', is also shown for positively holding the die-carrier in a position in which the adjusted 5 die is located at the working point, this pin 44 being insertible in any one of a number of openings 44'' properly coöordinated with the several dies mounted upon the carrier. In the practical use of this mechanism of 10 Figs. 5, 6, and 7, each type is produced as the result of the conjoint effect of the feeding movement of the two members together (which movement may be of a different character than that here accomplished, as was 15 before explained), during a part at least of which movement the blank is oscillated to-and-fro about an axis extending longitudinally thereof and preferably located adjacent to its upper edge. Although the function of 20 this mechanism is in part to effect a subsidiary movement in the nature of an oscillation about an axis which remains fixed during its occurrence, I do not design that the present method shall be limited to the making 25 of types by oscillating the members relatively to one another about such an axis, since this axis may shift during the type-making at a uniform speed equal to that at which the members are fed together or at a 30 different rate, these special modes of making types being set forth in other applications filed by me and before referred to. The blank-holder of this mechanism is, as before, designated by H, and the blank therein by G, 35 the latter being held in position by clamping-screws 23, 23, as already described. In this case, however, the blank-holder is supported in a rock-frame N pivoted by pins 45, 45 at opposite ends, which pins are screwed into 40 the side pieces 41, 41' of the framework and enter pivot openings in upright portions 46, 46 of the frame N, being held in an adjusted position by check-nuts 45', 45'. A feed-screw for producing a longitudinal traverse 45 of the blank-holder, and the contained blank is designated as before by 34. The means herein shown for oscillating the frame N, and hence the blank-holder H and its contained blank, about the axis defined by the pivot-pins 50 45, 45 comprises a driving-shaft S', suitably journaled in bearings in the framework and driven by means of a pulley 15' for instance from a suitable source of power, (not shown). This driving-shaft S' carries 55 an eccentric 47', from which motion is transmitted to an oscillator-plate through a link 48, operatively connected at one end with the periphery of the eccentric and at the opposite end pivoted to arms 49, extending from 60 the oscillator-plate 47 pivotally supported by suitable means to swing about an axis. Obviously when the shaft S' is rotated an oscillatory motion will be imparted to the plate 47, which motion may be transmitted 65 to the frame N in the manner shown, that is,

by means of a link 50, pivoted at one end to a projection on said frame and at the opposite end to a proper pivot-pin 50' operatively related to the plate 47.

I have shown in the mechanism of Figs. 5, 6, and 7 means for varying the amplitude of the angular movement imparted to the frame N during the rotation of the shaft S', since in some cases it may be desirable to vary the extent of the excursions from side to side of the blank at different stages of the type-formation, as more fully described in my application Serial No. 740,512 filed December 16, 1899, respectively, to which reference may be made, as I do not contemplate that the present broad and general mode of making types shall be restricted to a mode of type-making in which the subsidiary or to-and-fro movement necessarily varies or is reduced during the later stages of the type-making operation. The device for this purpose as herein shown is of the simplest construction, comprising a hand-lever 51, operative for the actuation of an arm 52, engaging at its outer end with the part from which the pivot-pin 50' of the lever 51 extends. This said part, in order to enable the throw of the pin 50' to be varied, is in the nature of a block adapted to slide toward and away from the pivotal axis of the oscillator-plate 47. The lever 51 is in this case mounted upon a shaft 53 being rigid with a sleeve or barrel 51' for the purpose, and the shaft 53 extending between the side pieces 41, 41' of the frame. Combined with the lever 51 is a stop-pin 53' for limiting the outward movement of the slide-block in one direction, while a spring 54 encircling the barrel 51' serves to urge the parts in a position in which the axis of the pivot-pin on the slide-block coincides with the axis of oscillation of the oscillator-plate 47, corresponding to a position therefore in which no oscillatory motion is imparted to the frame and even though the oscillator-plate 47 be in rapid oscillation about its axis.

In all the mechanisms so far described, the construction is such as to cause a positive and mechanically guided movement of each point of the several die-faces along a curved path relatively to the corresponding point of the blank with which each such point of the die comes in contact and with reference to which it acts as a forging or swaging tool, although it will be understood that this motion is of relatively small extent. That is to say, the movement imparted to either member is such as to positively vary the angular relation of the axis of the die to that of the forming type first to one side and then to the other. The result, therefore is to accomplish a treatment of the stock of the blank which may be defined as a rolling treatment alternating first in one direction and then in the opposite. The present method of making types and lines of types is not, however, and as before men-

tioned, limited to such particular species of subsidiary motion effective to accomplish the desired result in conjunction with a feeding movement, since I deem it within the 5 scope of the present method of making types that this subsidiary motion be of any species, provided it is effective conjointly with the feeding of the members together, to constitute such a working engagement as will sub-
 ject the stock of the blank to successive, 10 repeated actions or forces, and by repeated reductions and through successive shapings work the stock into a form which is a substantially exact counterpart of the type-
 making instrumentality or die. Thus, as a 15 species of subsidiary movement differing somewhat in character from that already described, the members may be moved to and fro relatively to each other while in contact
 20 one with the other along a substantially straight line. A conventional form of mechanism for producing a subsidiary movement so characterized is disclosed in Fig. 8. In the mechanism there set forth B'' as before
 25 indicates the supporting framework; C'' the die-carrier having dies D mounted thereon, while the locking pin 44, provided with a head 44' is shown being adapted to be inserted in any one of a series of openings 44'' for the
 30 purpose of locking the die-carrier in an adjusted position. G designates the blank adapted to be held in a suitable blank-carrier or holder H by means of clamping-screws 23, 23 and in this case the blank is fed against
 35 the die in a manner corresponding to that effected by the construction set forth in Figs. 1 to 4, inclusive, the slide 24 upon which the blank support H is mounted being adapted for movement toward and away from the die-
 40 carrier in slides secured to or formed in the framework of the mechanism. A lever 25', corresponding to the described lever 25, is similarly pivoted at one end to the framework B'' while at its opposite end it carries a
 45 cam-roller 26', in operative engagement with a cam 27', secured to a shaft 28'. Intermediate its ends the lever 25' is pivoted to the slide 24 upon which the blank - carrier is mounted.
 50 In the organization shown rotative motion is imparted to the shaft 28' by a construction similar to that set forth in Figs. 1 to 3, inclusive, this construction comprising a pawl 30' engaging with the ratchet-wheel
 55 31', affixed to the shaft 28', and operative from a crank-pin 29', driven from a shaft S'', a spring s being provided extending between a fixed pin s', projecting from the base of the framework, and an arm s'' fixed with relation
 60 to the pawl 30' for holding the pawl in engagement with the ratchet-wheel. The shaft S'' constitutes the driving-shaft of the mechanism, and it may be driven in any desired and suitable manner, as by a driving-
 pulley 15'', rotated from a suitable source of power (not shown). The die-carrier C'' is mounted, as in Fig. 1, upon a slide 4, but in this case the die-carrier is designed to have a small to-and-fro movement unaccompanied by any rotation about its own axis (see the 70 full and dotted positions of the die y, y', respectively, in Fig. 9), the locking pin 44 precluding this latter movement. This slide 4 is moved to and fro in its guides in the present construction by the following means; an 75 actuator-arm 55 enters at its upper end an opening 55' in such slide, while its lower end is adapted to be vibrated to and from the crank-pin 29' by means of a connecting link 56, which is in operative connection at one 80 end with the crank-pin and at the opposite end is pivoted to such rod. Intermediate its ends the actuator rod is pivoted to a link 57, hinged in this case to the framework of the mechanism, and serving as a fulcrum 85 about which the actuator rod may oscillate and thereby impart a to-and-fro movement to the slide. This mechanism, like those already described, is capable of varying the extent of the to-and-fro movement of the 90 slide, although the present method of making types, as already stated, is not limited to a variation of this character. The means here shown for accomplishing this result consists of a cam 58, secured to the shaft 28', 95 this cam being effective, when the shaft is rotated, to elevate or depress the fulcrum link 57 through a cam-roll 59 mounted upon the link and bearing against the cam. Evidently from the construction shown in Fig. 8 100 the higher the link 57 is elevated the more nearly will the point of contact of the slide 4 with the actuator rod approach the fulcrum point of the link 57 about which the crank-pin 29' causes the actuator to oscillate. The 105 construction is designed to be such that when the outer end of the link 57 is tilted upward and assumes its highest point, as the result of the operation of the cam 58, practically no motion will be imparted to the slide upon 110 which the die-carrier is mounted even though the shaft S'' be in constant rotation. A clutch device similar to that shown in Figs. 1, 2, and 3 may be employed for starting and stopping the movement of this shaft S''. 115
 Assuming now that a die has been brought to the working point and engaged with the blank, and that a relative subsidiary motion of the general nature described (particular species of which the various mechanisms set forth are capable of producing) has been imparted to the members, the various faces and elements of the die perform particular functions which coöperate with each other, in general, in varying relations not only as to coincident performance but also as to amount. Material lying in the edge of the blank in excess of that 120 125

necessary for building up and forming the type-block is dislodged from its position as the die advances into the blank, and the subsidiary motion is imparted to the members transversely to the line of length of the blank. The shearing edges of the die alternately bite afresh into the material, and the latter is forged first on one side and then on the other and worked into form by progressive shapings, being forced upwardly into the cavity of the die, until ultimately, the hair-line spaces and crevices at the bottom of the die-cavity, and which serve to give form and shape to the type-lines, are filled with stock which is swaged to form and the various faces of the type highly finished as the die continues its action. Each type is thus produced having a truly wrought character and possessing advantages, as regards dense conditions of mass and smoothness of surface, exhibited by highly wrought surfaces.

A mode of operation precisely similar to that according to which each die forms its type may be utilized for forming word and other spaces, a proper die of the necessary width being of course used.

Material in excess of that needed for the making of the type-block and which is forced beyond the planes of the sides of the blank may afterward be removed or trimmed in any suitable manner for the purpose of bringing the sides of the bars into parallelism with each other and producing a finished product.

During the successive to-and-fro or alternating movements there is, according to the preferred mode of operation, a constant advance of the die relatively to the blank, and at no time is the die withdrawn from the partially formed type, as the present method will usually be practiced. When the die is moved in one direction, or shifted for the purpose causing one side or wall of the die to forge or shape the type, all the other parts and faces of the die are also approximately in position, and in point of fact, the type body is inclosed within the space of the die, thus preventing any considerable shifting of the position of the type with regard to the die. According to this feature of the operation, therefore, the edges and faces of the forming type are positively controlled during the entire operation of making each successive type on the blank, with the result that a high degree of uniformity is exhibited individually and collectively by the line of types.

While the practice of the present mode of making types and lines of types is not limited to any particular construction of dies, dies may be used which perform functions additional to those of working the type-block to shape and dislodging and forcing out excess material. Thus the die may be of such a character as to preliminarily prepare that

portion of the blank in advance of the forming type, and thereby facilitate the action and operation of the die next selected and brought into operative engagement with the type-blank.

Having described my invention, I claim—

1. That improvement in the art of making a character, which consists in subjecting the blank upon which the character is to be made to a repeated treatment first on one side and then on the opposite side applied transversely to the line joining the character-field of the forming character with the character-field of an adjacent character. 65

2. That improvement in the art of making a character, which consists in subjecting the blank upon which the character is to be made to a repeated forging treatment first on one side and then on the opposite side applied transversely to the line joining the character-field of the forming character with the character-field of an adjacent character. 70

3. That improvement in the art of making a character, which consists in subjecting the blank upon which the character is to be made to a repeated forging and swaging treatment first on one side and then on the opposite side applied transversely to the line joining the character-field of the forming character with the character-field of an adjacent character. 75

4. That improvement in the art of making a character, which consists in subjecting the blank upon which the character is to be made to a repeated treatment first on one side and then on the opposite side applied transversely to the line joining the character-field of the forming character with the character-field of an adjacent character. 80

5. That improvement in the art of making a character, which consists in subjecting the blank upon which the character is to be made to a repeated forging treatment first on one side and then on the opposite side applied transversely to the line adjoining the character-field of the forming character with the character-field of an adjacent character, and simultaneously working excess material laterally of the blank. 85

6. That improvement in the art of making a character, which consists in subjecting the blank upon which the character is to be made to a repeated forging and swaging treatment first on one side and then on the opposite side applied transversely to the line joining the character-field of the forming character with the character-field of an adjacent character, and simultaneously working excess material laterally of the blank. 90

7. That improvement in the art of making a character, which consists in feeding a die

and a blank together and during the action of the die imparting a relative subsidiary movement to the members to and fro in a plane for the purpose of gradually and progressively forming a type by successive and repeated shapings.

8. That improvement in the art of making a type, which consists in subjecting the blank upon which the type is to be made to a repeated treatment first on one side and then on the opposite side applied transversely to the line joining the character-field of the forming type with the character-field of an adjacent type.

15 9. That improvement in the art of making a type, which consists in subjecting the blank upon which the type is to be made to a repeated forging treatment first on one side and then on the opposite side applied transversely to the line joining the character-field of the forming type with the character-field of an adjacent type.

10 10. That improvement in the art of making a type, which consists in subjecting the blank upon which the type is to be made to a repeated forging and swaging treatment first on one side and then on the opposite side applied transversely to the line joining the character-field of the forming type with the character-field of an adjacent type.

25 11. That improvement in the art of making a type, which consists in subjecting the blank upon which the type is to be made to a repeated treatment first on one side and then on the opposite side applied transversely to the line joining the character-field of the forming type with the character-field of an adjacent type, and simultaneously working excess material laterally of the blank.

30 40 12. That improvement in the art of making a type, which consists in subjecting the blank upon which the type is to be made to a repeated forging treatment first on one side and then on the opposite side applied transversely to the line joining the character-field of the forming type with the character-field of an adjacent type, and simultaneously working excess material laterally of the blank.

45 50 13. That improvement in the art of making a type, which consists in subjecting the blank upon which the type is to be made to a repeated forging and swaging treatment first on one side and then on the opposite side applied transversely to the line joining the character-field of the forming type with the character-field of an adjacent type, and simultaneously working surplus material laterally of the blank.

55 60 14. That improvement in the art of making a type, which consists in feeding the die and the blank for the reception of a plurality of types together and during the action of the

die imparting a relative subsidiary movement to the members to and fro in a plane for the purpose of gradually and progressively forming a type by successive and repeated shapings.

15. That improvement in the art of making a line of type by making and completing each type before the next type is begun, which consists in applying the proper dies successively at successive points along the length of the blank, and during the application of each die imparting to the members a relative subsidiary movement.

16. That improvement in the art of making a line of type, which consists in applying the proper dies successively at successive points along the length of the blank, and during the application of each die imparting to the members a relative subsidiary movement transversely to the line of length of the series of types when formed.

17. That improvement in the art of making a line of type by making and completing each type before the next type is begun, which consists in subjecting the material of the blank to the repeated treatment of selective type making instrumentalities, selectively brought into an operative position, such repeated treatment resulting from the feeding of the blank and the operating die together accompanied by a relative subsidiary movement of the type making members.

18. That improvement in the art of making a line of type by making and completing each type before the next type is begun, which consists in subjecting the material of the blank to the repeated treatment of selective type making instrumentalities, selectively brought into an operative position, such repeated treatment resulting from the feeding of the blank and the operating die together accompanied by a relative subsidiary movement of the type making members, in a direction transverse to the line of length of the line of type being formed.

19. That improvement in the art of making a line of type which consists in subjecting the material of the blank to the repeated treatment of type making instrumentalities, such repeated treatment resulting from the feeding of the blank and the dies together accompanied by a relative subsidiary movement of the type making members.

20. That improvement in the art of making types which consists in moving the die under pressure against the blank in various directions until the type is formed and then moving die and blank with relation to each other to make the next type.

21. That improvement in the art of making characters which consists in subjecting a character field of the blank to a repeated forging treatment, alternately upon its re-

spective sides, applied transversely to the line joining such character field with an adjacent character field.

22. That improvement in the art of making a type, which consists in setting off a type-blank on the edge of a typebar blank, subjecting opposite walls of the type-blank to a progressive forging operation during the

setting off of said type-blank, and compressing the face of the type-blank in contact with a type-die.
